US00D801308S

(12) **United States Design Patent** (10) Patent No.: **US D801,308 S**
Ahn et al. (45) Date of Patent: ** Oct. 31, 2017

(54) **SPEAKER**

(71) Applicant: **Samsung Electronics Co., Ltd.**, Suwon-si, Gyeonggi-do (KR)

(72) Inventors: **Daekyung Ahn**, Namyangju-si (KR); **Inshik Kim**, Seongnam-si (KR); **Jinwook Kim**, Yongin-si (KR); **Sangmin Hyun**, Seoul (KR)

(73) Assignee: **SAMSUNG ELECTRONICS CO., LTD.**, Suwon-si (KR)

(**) Term: **15 Years**

(21) Appl. No.: **29/541,317**

(22) Filed: **Oct. 2, 2015**

(57) **CLAIM**

We claim the ornamental design for a speaker, as shown and described.

DESCRIPTION

FIG. 1 is a front perspective view of a speaker showing our new design.

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines illustrating portions of the speaker are for environmental purposes only and form no part of the claimed design.

1 Claim, 8 Drawing Sheets
